G. U. ANGEVINE

DRAPEY HANGER

Filed May 7, 1921

UNITED STATES PATENT OFFICE.

GLENN U. ANGEVINE, OF CHICAGO, ILLINOIS, ASSIGNOR TO GLENN U. ANGEVINE AND AUGUST H. SCHALLOCK, COPARTNERS DOING BUSINESS AS THE G. U. ANGEVINE COMPANY, OF CHICAGO, ILLINOIS.

DRAPERY HANGER.

Application filed May 7, 1921. Serial No. 467,777.

To all whom it may concern:

Be it known that I, GLENN U. ANGEVINE, a citizen of the United States, residing at Chicago, in the county of Cook and State 5 of Illinois, have invented certain new and useful Improvements in Drapery Hangers, of which the following is a specification.

This invention relates to drapery hangers and is concerned particularly with the provision of an especially serviceable duplex hanger of this kind which can be sewed to the edges of the draperies at a minimum labor cost and which, furthermore, is especially adapted for production in commercial 15 quantities at a low manufacturing cost.

I am aware that numerous kinds and forms of drapery hangers have been proposed heretofore, but these have invariably comprised either complicated arrangements 20 of a comparatively great number of parts not commercially feasible of production or else they proved to be unsatisfactory and generally impractical because of the prohibitive labor cost incurred in sewing them on 25 the edges of the draperies.

The novel features of my improved form of drapery hanger will be discussed more fully in the following description which is to be read in connection with the accompanying drawing wherin Figure 1 is a perspective of the hanger illustrated in the course of attachment to the draperies. One drapery only has been illustrated sewed to one side of the hanger and none to the other 30 side, in order not to obscure the hanger and also to demonstrate better the facility with which the hanger may be fastened to the drapery. Fig. 2 is a front elevation of the hanger secured at opposite sides to draperies and positioned astride a drapery supporting rod. Fig. 3 is an end elevation of the hanger detached, and Fig. 4 is a horizontal section taken on line 4-4 of Fig. 2 35 looking in the direction indicated by the arrows.

The same reference numerals apply to corresponding parts in the three views.

In the drawings the reference numeral 5 represents the hanger which is adapted to carry a set of two draperies 6-6 on opposite sides of a supporting rod 7. The hanger consists of an inverted substantially U-

shaped brace or sub-frame 8 to the legs of which are secured strips 9-9 for carrying draperies. These strips are slightly longer 55 than the legs 10 of the sub-frame so that they project a substantial distance above the arched portion or bridge 11 spanning the hanger between the strips 9. The strips are fastened to the legs 10 of the sub-frame by 60 means of eyelets 13. The eyelets together with the openings 14 punched in the upper ends of the strips 9 serve to admit the seamstress's needle in making the stitches 15 which hold the hanger to the edge of the drapery. 65 When the draperies are in place, as shown in Fig. 2, they effectually conceal both the rod 7 and the hangers 5 and make a presentable appearance.

It will be observed with what ease the 70 hanger can be sewed to the drapery. In hangers of the duplex type used before, the bottom portion was not open as at 16 so that the seamstress in sewing the hanger on the edge of the drapery had considerable difficulty. In order to make a stitch it was necessary to pass the needle through the loop afforded to receive the rod 7 and besides there was the necessity always of inserting 75 the needle at an angle, which frequently resulted in breaking the needle and considerable delay generally which, of course, greatly increased the labor cost and discouraged the use of these hangers.

A pin 18 joins the legs of the frame and 80 has reduced ends 18^a which pass through openings in the frame and are upset on the outside of the strips 9, as shown in Fig. 4. It will be seen that the pin 18 thereby constitutes a substantial rigid brace which 85 holds the legs of the frame spaced properly. This pin serves also as an axle for the anti-friction roller 19 which is preferably grooved to conform to the rod 7 on which it rolls. Spacing rings 20 are interposed 90 between the roller 19 and the legs of the frame to maintain at all times proper relation of the roller and to keep an even keel as the hanger is moved along the rod. The arched brace 11 besides serving as a dust-guard for the roller 19 and its spacers, may 95 be slightly yieldable so that, for example, if the drapery becomes caught or is pulled carelessly, the frame will yield slightly and

the strain on the stitches 15 cannot therefore be sufficient to tear them.

It was customary in this art to provide in connection with the drapery rod usually a pair of rollers rather narrow and frequently on arcuate axles. These hangers were not satisfactory because the rollers would bind on their axle and would also cut the drapery rod; also they were very noisy in operation on account of the looseness and frailty of the parts. With the arrangement herein shown these objections are entirely obviated.

The foregoing description is to be considered as illustrative merely as it will be apparent that the invention is capable of considerable modification and adaptation within the spirit and scope of the appended claims.

I claim as my invention:

- 20 1. A hanger of the character described comprising a frame having a pair of straight laterally spaced legs which incline inwardly toward each other toward the bottom adapted to admit freely between them the supporting rod for said hanger, a single anti-friction bearing roller having the periphery thereof conformed to the contour of said rod to roll thereon, a straight pin for said roller extending across the hanger between said legs and secured thereto to constitute a rigid brace for said frame, and spacers on said pin for spacing said roller relatively to said frame, said frame comprising a substantially U-shaped brace fastened on the inside of the lower portion of said legs by a plurality of eyelets adapted to receive drapery securing means and

having its arched portion extending across said frame over said roller and serving as a dust-guard therefor.

2. A duplex drapery hanger of the character described comprising a pair of straight laterally spaced legs constituting the frame for said hanger open at the lower end so that said hanger may be placed astride the supporting rod for the draperies, a single anti-friction roller in said frame adapted to roll on said rod, a straight pin serving as an axle for said roller and joining said legs to constitute a rigid brace therefor, spacers for said roller to maintain said frame in proper relation to the supporting rod, and a U-shaped brace for said frame disposed below the upper ends of said legs and having its cross piece arched over said roller and acting as a dust-guard therefor.

3. A duplex drapery hanger comprising an inverted U-brace formed of flat strip material and adapted for straddling a drapery rod, a pair of flat drapery-attaching strips fastened by their lower portions to the legs of said U by eyelets to provide convenient openings to receive stitches for fastening draperies and having holes therein above said U for a similar purpose, a straight pin extending across the hanger between the legs of the U, and a single roller mounted thereon to turn but prevented from sidewise movement, said roller being annularly grooved in the middle thereof to fit the drapery rod.

In testimony whereof, I have hereunto set my hand.

GLENN U. ANGEVINE.
